GIRDLE OR THE LIKE

Jean Glosios, New York, N. Y.

Application November 1, 1948, Serial No. 149,431

Term of patent 7 years

(Cl. D20--2)

To all whom it may concern:

Be it known that I, Jean Glosios, a citizen of the United States, residing in the city of New York, in the county of New York and State of New York, have invented a new, original, and ornamental Design for a Girdle or the like, of which the following is a specification, reference being had to the accompanying drawing, forming part thereof.

I claim:

The ornamental design for a girdle or the like, as shown.

JEAN GLOSIOS.
